UNITED STATES PATENT OFFICE

CHARLES F. HUMPHREYS AND HENNING W. PRENTIS, JR., OF LANCASTER, PENNSYLVANIA, ASSIGNORS TO ARMSTRONG CORK COMPANY, OF LANCASTER, PENNSYLVANIA, A CORPORATION OF PENNSYLVANIA

LINOLEUM

Application filed March 30, 1927. Serial No. 179,710.

The present invention relates to linoleum, and more particularly to a linoleum containing lustrous materials whereby a desired texture or color may be imparted to the linoleum.

We provide a linoleum containing a lustrous material which imparts a desired color or texture to the linoleum. The lustrous material may comprise a finely divided metallic substance, such as aluminum or bronze powder, or lustrous mineral matter, such as mica, which are particularly effective in the formation of an imitation marble or tile. The added material may be used to replace a certain proportion of the usual inert ingredient in linoleum, or may be added to the regular linoleum mix.

In the accompanying drawing, illustrating certain embodiments of the invention,

Figure 1 is a sectional view through a piece of linoleum having the lustrous materials uniformly distributed therethrough; and

Figure 2 is a similar view showing a modified structure.

The linoleum illustrated in Figure 1 comprises a backing 2 having a body 3 of linoleum composition thereover. Mixed into this body material is the lustrous material such as metallic powder or the like. The particles are diagrammatically illustrated at 4.

We prefer to add the metallic or mineral substance to the mix just before the mix is applied to the backing. In other words, we do not prefer to have the metallic or mineral substance intimately mixed with the other constituents in the regular mixing machine. We have found that passing the lustrous substance through the regular mixing machine results in a dull finish, possibly because of an oil film completely surrounding the individual particles. When the metallic substance is added subsequently to the thorough mixing of the linoleum ingredients and is simply stirred through the same without an intimate mixture being effected, the resulting linoleum has a metallic lustre, and many desired texture effects can be produced by suitable proportioning of the various ingredients.

If desired, the powdered metal may be dropped on top of the mix so that it forms a

superficial coating on the finished linoleum. This will give a metallic sheen to the surface, but does not provide a linoleum which will maintain its original appearance after having been worn. We prefer to mingle the lustrous substance with the various linoleum constituents prior to application thereof to the backing so that the particles are dispersed through the finished linoleum and the desired texture effect still remains after the surface has been worn.

A linoleum wherein the lustrous particles are confined to the surface is illustrated in Figure 2 which shows a material having a backing 5 and a body 6 of linoleum composition. The particles of lustrous material lie in or on the surface and are diagrammatically illustrated at 7.

Pleasing effects may be obtained in all types of linoleum by the inclusion of lustrous materials therein; various colors may also be imparted to the linoleum and delicate shadings may be had.

Lustrous minerals, such as mica, are desirable in marbelized linoleum and tile patterns, a haphazard occurrence of the mica gives an appearance of natural stone or tile. For example, a surface covering simulating hand-laid tile, such as disclosed in United States Reissue Patent No. 16,473, of November 16, 1926, having certain portions varying strikingly from the remaining portions of the covering, is particularly adapted to the application of our invention. The tile-like units may include various lustrous materials enhancing their color value and prominence.

When forming a molded inlaid linoleum, the lustrous material is merely intermingled with other constituents, and the mixture is applied through the stencils in the usual manner.

Our invention is applicable to flexible, hard surfaced floor coverings of the linoleum type wherein a plastic mixture of ground cork is applied to a burlap backing. It is also applicable to coverings of the linoleum type which may include a plastic mixture other than cork, binders other than oil, and a backing other than burlap, such for example, as a plastic nitrocellulose backed with paper or felt.

Although we have described the preferred method of carrying out our invention, it will be understood that the lustrous minerals or metallic substances may be added to the linoleum mix at various stages in the process of making linoleum, depending upon the effects desired, and that the invention may be otherwise practised and embodied within the scope of the following claims:

10 We claim:

1. The method of making molded inlaid linoleum comprising mixing the usual ingredients, adding lustrous metallic particles thereto, effecting the cursory mixing of such particles with the mixture of usual ingredients and thereafter applying the resulting mix to a backing, whereby lustrous particles will appear in the surface of the linoleum to impart thereto a metallic sheen or lustre.
- 15 2. As an intermediate product in the manufacture of molded inlaid linoleum, a linoleum mix adapted for application through the stencils commonly employed in the manufacture of inlaid linoleum, and having lustrous particles distributed therethrough characterized by having their lustrous appearance undimmed by oil coatings or the like.
- 20 3. The method of making linoleum comprising effecting a mix of the usual ingredients, adding lustrous metallic particles thereto, mixing the mass sufficiently to incorporate the lustrous particles but insufficient to dim their lustre, and thereafter forming a sheet of linoleum from the mix.
- 25 35 In testimony whereof we have hereunto set our hands.

CHARLES F. HUMPHREYS.
